AUTOMATIC HOG FEEDER AND GRINDER

Original Filed Oct. 8, 1928

Attorney

UNITED STATES PATENT OFFICE

ALLAN J. McDougall, OF DENVER, COLORADO, ASSIGNOR OF ONE-HALF TO EDWARD J. JAMES, OF DENVER, COLORADO

AUTOMATIC HOG FEEDER AND GRINDER

Application filed October 8, 1928, Serial No. 311,052. Renewed February 13, 1931.

This invention relates to a stock feeding device, more particularly adapted to feed hogs, and has for its principal object the provision of a grain feeding device which will simultaneously grind the grain and be operated entirely by the animals.

Another object of the invention is to provide a device which will require some energy on the part of the hogs in order to obtain their feed, so that they will be kept in a constantly healthy and hungry condition.

A further object of the invention is to provide a device of this character which can be placed out of doors and which will entirely protect the contained grain from rain, snow, etc.

A still further object is to provide a hog feeding device which will prevent the larger and stronger hogs from crowding the smaller hogs away from the feed.

Other objects and advantages reside in the detail construction of the improvement, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a side elevation and vertical section of my improved hog feeder, the section being taken on the line 1—1, Fig. 2.

Fig. 2 is a horizontal section of the feeder taken on the line 2—2, Fig. 1.

Fig. 3 is an enlarged detail view of the supporting standard and its attachments.

Fig. 4 is a detail view illustrating a protecting flap with which the feed discharge openings may be provided.

The invention comprises a feed reservoir 10 arranged to discharge grain through grinding burrs 11 and 12 to a rotary feeding pan 13. The feeding pan 13 is provided with a series of feeding pockets 14 from which the hogs receive their feed.

The entire device is supported upon a central standard 15 which is carried in a suit-

able supporting base 16. The feed reservoir 10 rests on, and is secured to, a supporting flange 17 which in turn is welded or otherwise formed on the lower extremity of a sleeve 18 surrounding the standard 15. The upper portion of the reservoir 10 is braced from the sleeve 18 by means of suitable brace bars 19.

The sleeve 18, and with it the reservoir 10, can be raised or lowered upon the standard 16 by means of an adjusting nut 20 threaded on the standard. The nut 20 is provided with hooked members 21 which engage under a flange 22 on the upper extremity of the sleeve 18 so as to support the sleeve and its attached mechanism.

The feed reservoir 10 and the sleeve 18 are locked from rotation about the standard 15 by means of a pin or bolt 38 which passes through the sleeve 18 and the standard 15. In the sleeve 18 the bolt 38 passes through slotted openings 39 which allow vertical movement of the sleeve.

The upper grinding burr 11 is secured to the bottom of the supporting flange 17 immediately over the lower grinding burr 12.

The grain from the reservoir 10 flows to the grinding burrs 11 and 12 through one or more discharge openings 23 formed in the bottom of the reservoir 10 and through the supporting flange 17. The flow through the opening 23 can be controlled by means of a suitable valve 24.

The lower grinding burr 12 is carried on a supporting disc 25 surrounding the standard 15. The supporting disc 25 is rotatably supported on a ball thrust-bearing 26 from a set collar 27 upon the standard 15. The feed pan 13 is carried from the disc 25 upon a series of radial supporting arms 28. Through this construction the entire weight of the feed pan 28 and the lower grinding burr 12 is carried upon the thrust bearing 26.

The ground grain falls from the periphery of the grinding burrs into the feed pan 13 and is forced to the periphery of the feed pan by a series of stationary rake bars 29. The rake bars 29 extend tangentially from pivots 30 on a base ring 31. By securing the rakes 29 upon pivots on the ring 31 they are free to lie

on and follow the plane of the feed pan bottom.

The ring 31 is clamped to the standard 15 immediately above the bottom of the feed pan 13 by means of a suitable clamp 40. The grain is forced through openings 32 to each of the feed pockets 14 by the action of the rakes 29.

In operation, the hogs will force their snouts into the feed pockets 14 in search of the grain. The pockets all open at a tangent to the periphery of the feed pan 10 so that, in feeding, the hogs will push the pockets forwardly causing the feed pan 13 to revolve. The rotation of the feed pan under the stationary rakes 29 causes the grain to travel outwardly in the pan into the pockets 14. As the feed pan 13 rotates it will rotate the lower grinding burr 12 against the grinding surface of the upper grinding burr 11, thus grinding the grain flowing from the reservoir 10 before its deposit in the feed pan 13. The upper grinding burr is constantly maintained stationary by being secured to the stationary reservoir 10.

The separation of the grinding burrs 11 and 12 and the degree of grinding can be minutely regulated by turning the adjusting nut 20, which will separate or bring the grinding burrs together, as desired.

The reservoir 10 is closed by means of a weather tight cover 33 secured in place by an ornamental nut 34 upon the upper extremity of the standard 15. The feed pan 13 is protected from the weather by a conical shield 35 which extends outwardly over the pan and has a depending lip 36 surrounding the pan.

To assist in directing the grain toward the discharge openings 23, a hopper 37 may, if desired, be placed in the bottom of the reservoir 10.

It has been found by actual practice that the hogs quickly learn that rotation of the feed pan will furnish them with food, so that they are willing and anxious to operate the feeding and grinding mechanism. The hogs do not follow any certain pocket around the device but soon learn to push one pocket away from them and start feeding on the next following pocket. They will be found to stand in a circle about the device pushing the pockets from one to another as they feed. As the pockets approach the next hog they will again be filled by passing one of the rakes 29. This prevents the larger hogs from crowding the smaller ones away, since they do not leave the positions at which they started to feed.

Any number of the openings 23 and the rakes 29 may be employed as desired, depending upon the number of hogs being fed. The greater the number of rakes the more rapid will be the filling of the pockets.

In using this device the reservoir 10 can be filled with unground grain sufficient to last

for several days and during that period the hogs will require no attention to their feed.

If it is desired to prevent snow from blowing into the feed pan 13 from the feed pockets 14, flaps 41 may be provided hinged at 42 above the openings 32 as shown in Fig. 4, so that the grain can be forced outwardly into the pockets, but snow and rain can not be blown inward into the pan.

While a specific form of the improvement has been described and illustrated herein, it is desired to be understood that the same may be varied, within the scope of the appended claims, without departing from the spirit of the invention.

Having thus described the invention, what I claim and desire secured by Letters Patent is:—

1. A hog feeding and grain grinding device comprising: a vertical supporting standard; a sleeve surrounding said standard; means for supporting said sleeve at any desired vertical height on said standard means for preventing rotation of said sleeve about said standard; a grain reservoir secured to said sleeve; a grinding burr secured to the bottom of said grain reservoir; a feed pan rotatably supported from said standard below said reservoir; a second grinding burr operatively connected to said feed pan so as to co-operate with said first grinding burr; and a series of feeding pockets at the periphery of said feeding pan, said pockets being arranged to cause the animals in feeding to act at a tangent to the periphery of and rotate said feed pan, there being a series of openings communicating between said feeding pan and said pockets and stationary rake means within said feeding pan arranged to force the ground grain delivered by said burrs toward said openings as said pan is rotated.

2. An animal feeding and grain grinding device comprising: a vertical supporting standard; a lower grinding burr adapted to rotate about and adjacent the lower extremity of said standard; arms secured to and extending outward from said burr; a circular feeding pan suspended from said arms so as to rotate with said burr; feed pockets formed on the periphery of said pan; a sleeve surrounding said standard above said lower burr; means for preventing said sleeve from rotating about said standard; a feed reservoir carried by said sleeve, said sleeve passing centrally through said reservoir; an upper grinding burr secured to the bottom of said feed reservoir and arranged to co-operate with said lower grinding burr, there being a passage between said reservoir and said burrs; and means for securing said sleeve at any desired height on said standard so as to adjust the space between said burrs.

3. An animal feeding and grain grinding device comprising: a vertical supporting

standard; a lower grinding burr adapted to rotate about and adjacent the lower extremity of said standard; arms secured to and extending outward from said burr; a circular 5 feeding pan suspended from said arm so as to rotate with said burr; feed pockets formed on the periphery of said pan; a sleeve surrounding said standard above said lower burr; means for preventing said sleeve from 10 rotating about said standard; a feed reservoir carried by said sleeve, said sleeve passing concentrically through said reservoir; an upper grinding burr secured to the bottom of said feed reservoir and arranged to co-operate 15 with said lower grinding burr, there being a passage between said reservoir and said burrs; means for securing said sleeve at any desired height on said standard so as to adjust the space between said burrs; and rake 20 arms fixedly secured to said standard immediately above the bottom of said feeding pan and arranged to force grain toward its periphery.

25 In testimony whereof, I affix my signature.
ALLAN J. McDougall.
